UNITED STATES PATENT OFFICE.

FRANK C. STURGES, OF WILKES-BARRÉ, PENNSYLVANIA, ASSIGNOR TO THE WILKES-BARRÉ MOLDING MACHINE COMPANY, OF PENNSYLVANIA.

METHOD OF FORMING MOLDS.

SPECIFICATION forming part of Letters Patent No. 443,687, dated December 30, 1890.

Application filed February 7, 1890. Serial No. 339,565. (No model.)

To all whom it may concern:

Be it known that I, FRANK C. STURGES, a citizen of the United States, residing at Wilkes-Barré, in the county of Luzerne, in the State of Pennsylvania, have invented certain new and useful Improvements in the Method of Forming Molds, of which the following is a specification.

My improvements relate generally to the construction of sand molds by machinery, and relate particularly to that class of said molds which are employed in the casting of car wheels, and in connection with, and between the combined sections of which, cast iron or other chills are usually employed.

In Letters Patent of the United States No. 360,086, dated March 29, 1887—No. 360,119, dated March 29, 1887—No. 371,820, dated October 18, 1887—No. 408,579, dated August 6, 1889—and No. 409,667, dated August 27, 1889, are shown described and claimed sundry methods of and apparatus for forming molds for molding car wheels, in the practice of which methods and the operation of which apparatus, a pattern is pressed into the sand, making an imprint, which pattern, by the same operation, rams or compresses the sand to the required density.

It has been found difficult in operating the mechanism and in practicing the inventions embraced in the foregoing patents, to bring the pattern to the precise level of the flask wall, so that the chill, used in the casting of a car wheel, could take its bearing on the rim of the flask, and thus hold the mold firmly in place when it was closed and clamped to receive the metal; thus if the pattern did not descend to its proper place, the strain on the mold when closed and clamped, effected a compression of the sand under and over the chill and thus caused an irregular and de-

fective casting; again if the pattern descended below the proper point, the chill, taking its bearing on the edge of the flask, the parts of the mold, the cope, drag, and chill, were prevented from fitting closely together, whereby the molten metal was allowed to escape. To overcome these objections the practice has been to allow the pattern, which is a trifle smaller than the flask, to descend into the flask a short distance, and to place the

chill on the compressed sand inside the wall of the flask. This practice in a measure overcame said objections, but was itself objectionable in that the pattern, being of only 55 slightly less diameter than the inner wall of the flask, was liable, when in the act of descending into the flask, if for any reason the flask was not accurately centered, to come into contact with the walls of the flask and 60 thus occasion a breakage of a pattern or of some portion of the machinery. When the pattern was withdrawn from the flask loose particles of sand, caught between it and the flask, would fall upon the mold and thus necessitate a certain amount of hand labor in order to perfect the mold and put it in proper condition for closing and receiving the metal; and, finally, the chill, taking its entire bearing on the sand, was liable when the mold 70 was subjected to extreme pressure, to yield and thus cause an imperfect casting. I overcome all of these objections by adjusting the height of the flask wall, and the point to which the pattern shall descend so that 75 the pattern will under no circumstances descend down to the flask but to a point a short distance above it. I provide a flat surface on the rim of the flask and cause to be distributed on it, by suitable means, a 80 sufficient quantity of sand, and I extend the pattern so that it will overlap the outer wall of the flask, with the result that in the descent of the pattern the sand on the rim of the flask is compressed to a great degree of 85 hardness. On the compressed sand on the rim of the flask the chill finds a firm and rigid seat which will not yield when the mold is closed and clamped; no hand labor is required to perfect the mold, and there is no 90 danger of breakage by reason of the pattern striking the flask.

In the drawings, Figure 1 is a central sectional elevation of a complete mold provided with a chill, and containing a casting of a 95 double plate car wheel, which mold is of the character shown and described in United States Letters Patent No. 360,086, granted March 29, 1887, to Joseph J. Carr for method of molding car wheels. Fig. 2 is a central 100 sectional elevation of a flask in which the sand has been distributed in approximately

the form into which it is to be subsequently compacted by the pattern. Fig. 3 is a similar view of the same showing a sweep in operation upon said sand. Fig. 4 is a similar view of the same showing a pattern in place upon the sand, and Fig. 5 is a central sectional elevation of the cope and drag flasks of a mold, which mold embodies my invention and illustrates the relationship which the 10 chill bears to it when its parts are placed together, and shows in place in the mold a completed casting of a double plate car wheel.

Similar letters of reference indicate corresponding parts.

15 Referring first to Fig. 1 it will be seen that the sand contained in each flask is, as to its marginal portion between the matrix proper and the wall of the flask, flush or level with the rim of the flask wall, and that the chill 20 bears against the rim of each of said flasks. The molds of this figure are of the character heretofore in use, and herein before referred to.

25 In forming the mold according to the method which is the subject of my present application, I charge a walled flask with the sand or other molding material, extend a portion of the sand or molding material to and over the surface of the top of the wall of the flask, and fashion the sand contained in the body of the 30 flask with more or less accuracy into the form into which the sand is to be ultimately compressed; I then occasion the descent of a pattern of sufficient area to extend to the outer circumference of the flask whereby the sand 35 contained in the flask is compressed and formed into the desired ultimate shape, and the sand on the top of the flask wall is compressed to the required density to form the chill seat.

40 The following are the details of the operation thus briefly outlined:

45 The flask, A, in Fig. 2 is supplied with a quantity of sand, B, and said sand is distributed in any preferred manner within said flask to form which is, as stated, approximately that of the final desired form. A portion of said sand covers the edge of the wall a, as shown at b.

50 In Fig. 3 is shown a sweep C, consisting of a rigid arm c, and a roller, c', of corresponding outline to the arm, both designed to be mounted upon a vertical rotatable shaft,— both of the usual and general construction and mode of operation, and both of sufficient length 55 to extend over and therefore to operate upon the sand b upon the rim a, as well as upon the sand in the interior of the flask.

In Fig. 4 is shown the flask A and its contained sand B, and also a pattern D, of diameter sufficient to extend to the outer circumference of the flask, and therefore to operate upon the sand b upon the wall a as well as upon the sand contained in the flask,— which pattern is shown as down in place upon the sand. The position which said pattern D 60 is shown in the drawings as occupying, is the lowest which it is designed to reach, and the sand beneath it therefore is in the form which I herein term its ultimate form and in condition to be used in molding a wheel.

65 In Fig. 5 is shown a mold formed by the practice of my method, it being shown as holding between its cope and drag a chill E, while in the matrix is represented a cast car-wheel F.

I do not herein seek to cover the mold above 70 described as it forms the subject of a separate application for Letters Patent filed in the Patent Office February 7, 1890, as Serial No. 339,564.

Having thus described my invention, I 75 claim:

1. The method of forming a mold for casting car wheels, which consists in charging a walled flask with sand in which the matrix is to be formed, and in extending the sand of the 80 mold to and over the surface of the top of the wall or rim of the flask, and in then causing a pattern to descend upon both the sand in the body of the flask and the sand upon the top of the wall of the flask, as specified.

90 2. The method of forming a mold for casting car wheels, which consists in charging a walled flask with sand in which the matrix is to be formed, and in extending the sand of the mold to and over the surface of the top of the 95 wall or rim of the flask, and in then causing a pattern, the central portion of which is adapted to form the matrix of the wheel in the sand of the mold and the peripheral portion of which is adapted to form the seat for the chill on the sand above the rim of the flask and in the sand in that portion of the flask which is adjacent to its wall, to descend to form said matrix and to form said seat for the chill, as specified.

105 In testimony that I claim the foregoing as my invention I have hereunto signed my name this 27th day of January, A. D. 1890.

FRANK C. STURGES.

In presence of—

EDWARD E. HOYT,
ALEXANDER PATTERSON.
